UNITED STATES PATENT OFFICE.

CHARLES F. KETTERING AND WILLIAM A. CHRYST, OF DAYTON, OHIO, ASSIGNEES TO
THE DAYTON ENGINEERING LABORATORIES COMPANY, A CORPORATION OF OHIO.

SYSTEM OF SELECTIVE ELECTRICAL DISTRIBUTION.

1,264,943.

Specification of Letters Patent.

Patented May 7, 1918.

Original application filed November 20, 1912, Serial No. 732,483. Divided and this application filed May 1, 1916. Serial No. 94,684.

To all whom it may concern:

Be it known that we, CHARLES F. KETTERING and WILLIAM A. CHRYST, citizens of the United States of America, residing at Dayton, county of Montgomery, and State of Ohio, have invented certain new and useful Improvements in Systems of Selective Electrical Distribution, of which the following is a full clear, and exact description.

10 This invention relates to ignition systems such for example as are used with internal combustion engines, and has more particular relation to the combination of such a system with a starting system for starting the engine by a dynamo electric machine.

15 It is among the objects of the invention to arrange this system in such a manner that upon operating the ignition switch to close the ignition circuit, the engine starting device will at the same time be given an initial movement to facilitate the coupling of the starting device to the engine for cranking purposes.

20 Other objects will appear in connection with the ensuing description, having reference to the drawings accompanying this specification.

25 This present application is a division of original application, Serial No. 732,483, filed November 20, 1912.

30 The subject matter of the original application relates in general to various arrangements of ignition circuits and construction of so called push button switches for controlling the ignition circuits.

35 The present application relates to the combination of the ignition apparatus with the starting apparatus as above mentioned.

40 The original application just referred to, made reference to other applications upon which the improvements were based or which were referred to for more detailed description, and of these cases which were previously referred to, the present case relates 45 more particularly to an application which issued into Patent 1,150,523, dated August 17, 1915, and application 721,237, filed September 19, 1912.

45 Referring to the drawings:

50 Figure 1 represents a diagram of the electric circuits.

55 Figs. 2 to 6 inclusive, represent views of the push button switch mechanism.

Fig. 7 is a cross section of the double bind-

ing post which is preferable to embody in 55 the switch unit to facilitate the circuit connections shown in Fig. 1.

Fig. 8 is a fragmentary view of the coupling gearing for coupling up the electric motor with fly-wheel of the engine, for the 60 starting or cranking operation. This corresponds to a similar view in Patent 1,150,523, above referred to.

Fig. 9 is another diagrammatic view of the electrical circuits for the initial movement of the starting device. This view is in correspondence with a similar diagrammatic view of application 721,237, above referred to.

70 The general circuit arrangements according to Fig. 1 will first be described, in order to explain the push button arrangements for the ignition circuit, with general reference to the circuit for the preliminary starting operation.

75 There are four push buttons embodied in the push button switch, namely, 420, 421, 459 and 131.

80 The lower button 420 may for convenience be called the vibrator button, because when pressed in, it closes such an ignition circuit as to give what may be called a vibrator spark, in distinction to a single spark hereinafter referred to. It is this button which also serves to close another electrical circuit 85 for the purpose of giving the starting device the preliminary operation to facilitate coupling of the starting motor and engine together for cranking purposes.

85 The ignition circuit closed by this vibrator button 420 will first be described.

90 As soon as the button 420 is depressed, the contact plates 36^a and 35^a are separated, while the contact point 36^b is moved into engagement with the contact plate 178. Current will now flow from the battery 20, through wire 27, through the heavy winding 28 of the ignition relay device, across the contact plates 30 and 31, through the wires 600 and 609, thence to contact plate 36^a, through 95 the contact point 36^b, contact plate 178 to the timing device 25, via wire 601. This current then flows through the timing device 25 to the wire or conductor 602, through the primary winding 22 of the induction coil, 100 back to the battery, via the wire 24.

105 From the above, it will be seen that the current from the battery will pass through

the heavy coil or winding 28, and this winding 28 so energize the core 32 of the ignition relay, as to attract the armature 33, and thereby tend to effect the separation of 5 the contact plates 30 and 31, and this will of course cause a demagnetization of the core 32 and consequently permit the armature 33 to return to its normal position, again permitting the contact plates 31 and 30 to make 10 contact.

A repetition of the above operation will be effected, as long as current continues to flow through the main circuit. That is, the successive breaking and making of the main 15 circuit will be effected by the operation of the armature 33 and the consequent opening and closing of the contacts 30 and 31.

This successive breaking and making of the main ignition circuit will of course create 20 successive sparking impulses in the induction coil, and thereby furnish a succession of igniting sparks in the proper cylinders of the engine.

This type of ignition is well known in the 25 art as vibrating type ignition.

As stated above, the push button switch includes buttons 421 and 459. If the button 459 is depressed, the magneto system of ignition will be brought into operation by 30 the closing of the following circuit:

From the magneto 606, through wire 61, through contact plates 60 and 58, wire 62, through the resistance unit 57, and the primary winding 56 of the induction coil, 35 through the timer 51, thence back to the magneto 606.

When it is desired to use the single spark battery ignition, the button 421 is depressed, and providing the button 420 is in such 40 position as to permit the contact plates 36^a and 35^a to make contact, the following circuit will be closed:

From the battery 20, through wire 27, across the heavy coil 28 of the ignition relay 45 device, thence across contact plates 30 and 31, to the wire 600. From the wire 600, through the wire 607, contact plates 38 and 21, through the wire 608, thence to the wire 601, through the timer 25, wire 602, primary winding 22 of the induction coil, back 50 to the battery.

As soon as the current tends to pass through the coil 28, the core 32 of the ignition relay device will tend to become magnetized and attract the armature 33, so as to break the main circuit by the separation of the contact plates 30 and 31. As soon as this separation of the contact plates 30 and 31 occurs, and the main circuit is broken 55 in the manner described above, a supplemental or auxiliary circuit will be established, so that a small amount of current will tend to pass from the coil 28, through the fine winding 29, which is of much higher 60 resistance than the coil 28. This reduced

amount of current is only sufficient to maintain the core 32 of the ignition relay so magnetized as to maintain the armature 33 in position to separate the contact plates 30 and 31.

The current after passing through the fine winding 29, will pass through the wire 34, across the contacts 35^a and 36^a, thence through conductor 609, to the conductor 607, from which point, it will follow the course 70 of the circuit above described, that is, across the contacts 38 and 21, thence through wire 608, to wire 601, through timer 25, wire 602, primary winding 22 of the induction coil, back to the battery.

The flow of current through the fine winding 29 will continue until such time as the main circuit is broken at the timer 25.

It will therefore be seen that when the button 421 is in depressed position, the circuit arrangements will be such that only a single sparking impulse will be created in the induction coil for each time that the circuit is closed by the timer 25.

The operation of the starting circuit by 90 the same vibrator button 420 is as follows:

It will be obvious from Fig. 1 that the depression of the vibrator button 420 closes the contact at the point 438, so that the current from the storage battery 430 comes through the wire 439, to the contact point 438, button 420 to ground 435, then through ground 436 to wire 441, magnet coil 433, to dynamo electric machine 431, and thence back to the battery, via wire 440.

The flowing of the current through the magnet winding 433 operates the clutch 40 which is explained more in detail in the patent and application above referred to. In brief, this clutch 40 serves to connect up 105 the operating pedal in such manner that the depression of the operating pedal then establishes a connection between the starting motor and the flywheel of the gas engine. These parts are shown in Fig. 8 of the present drawings and operate as follows:

The depression of the clutch pedal 703 tends to effect the shifting of the clutch shaft 704 and consequently the shifting of the rod 48 which is connected to the shaft 115 in any suitable manner. This rod 48 is pivotally connected with the straight arm lever 49, which is pivoted at the point 50, while the opposite end thereof is connected to the rod 53. The lever 53 may have a 120 flexible connection, as is shown at 76, with the stud shaft 72, which is connected to the shiftable gearing, comprising the pinions 71 and 73, which constitute a means for coupling the electric machine 431 to the flywheel 125 705 of the engine.

Now, upon the actuation of the rod 48, due to the depression of the clutch pedal 703, the straight arm lever 49 will be shifted so as to pull the lever 53 in such a direction 130

as to draw the pinion 73 into enmeshment with the armature pinion 74 of the electric machine, and the pinion 71 into enmeshment with the teeth 710 of the flywheel 705, thus coupling up the engine and electric machine.

As explained more in detail in the above mentioned patent, the ordinary depression of the clutch pedal 703 does not effect the starter coupling operation. But, when the 10 push button 420 (Fig. 1) is operated, this sends the current from the battery, through the magnet 433, so as to operate the armature of the clutch 40. This clutch is likewise shown in Fig. 8, and when operated by 15 the magnet as described, this connects the clutch pedal 703 to the operating rod 48, in such manner that the depression of the clutch pedal operates the rods 48 and 53, to shift the coupling gearing in the manner 20 just described.

In order to facilitate the clear understanding of this arrangement with reference to the present description, a fragmentary portion of one of the views in application 25 721,237 (above referred to), is incorporated into the present application, namely in Fig. 9.

By referring to this figure, it will be seen that the depression of the aforesaid push 30 button 420, at the same time that it closes the circuit through the magnet coil 433, also establishes the circuit from the storage battery 430 through the dynamo electric machine 431.

35 The nature of the armature windings of this dynamo electric machine 431, utilized for the slow initial starting movement, as described in the application referred to, is such, (being of high resistance,) that the 40 flow of the battery current therethrough gives only a slow turning movement to the electric machine 431 so as thereby to facilitate the coupling of the electric machine to the flywheel of the engine.

45 Then, as soon as this coupling is effected, the continued movement of the operating pedal above referred to, and as explained in said application, throws the main switch for sending the electric current of the battery 50 through the motor windings of the electric machine, in order to give the cranking movement to the engine. These heavier motor windings are for convenience designated on Fig. 9 as 310.

55 The diagrammatic circuit arrangement of Fig. 9 is as follows:—

The movable element 98 of the main switch is normally in the position shown in full lines in Fig. 9. When the button 420, 60 (see Fig. 9) is depressed, it closes the contacts between 438 and 420, which will effect the closing of the following circuit:

From the battery 430, through the line 65 wire 440, to the common contact plate 103 of the main switch, thence through the mov-

able element 98 to the contact plate 104, thence through the armature windings of the electric machine 431, then through the magnet coil 433, wire 441, to the push button 420, across the contact plate 438, and the 70 wire 439, back to the battery.

The flow of current through the above mentioned circuit will effect a slow initial movement of the electric machine, because of using the high resistance armature windings of the dynamo electric machine 431. The flow of this current will also effect the 75 operation of the clutch 40 which tends to couple up the main operating pedal 703, in such a manner that when the pedal is depressed, connection will be established between the starting motor and the flywheel of the gas engine.

This slow initial movement is for the purpose of facilitating the enmeshment of the 85 coupling gears 74, 73, 71 and 710, so that the gear 74 of the electric machine is turning slowly while the operator is depressing the 90 pedal 703, and this insures easy enmeshment of the gears.

Now, as soon as the coupling gears have been enmeshed by this initial operation, the further movement of the pedal 703 effects the main cranking movement. The movable element 98 of the main switch is shifted into 95 dotted line position, (see Fig. 9,) and the circuit just described above will be broken and the following circuit will be established:

From the battery 430, through the wire 100 440, common contact plate 103, movable element 98 of the main switch, contact plate 105, thence through the low resistance armature windings of the electric machine. These 105 low resistance windings are for convenience designated as 310 in Fig. 9. From these windings 310, the current flows through wire 221 back to the battery, via wire 222. This circuit may be referred to as the starting or cranking circuit, and one which is brought into effect for the actual cranking operation. 110

The ignition circuit having meantime been closed by the button 420, the engine will now begin its self-operation as a result of this cranking movement.

If desired, the arrangement of the push 115 button 420 for closing the circuit to establish the slow initial movement, can be such as to carry out the circuit arrangements shown in the Patent 1,150,523 above referred to, but the particular form is not important, 120 it being sufficient merely for the purposes of the present case that the push button 420 when depressed, establishes the ignition circuit referred to, and at the same time provides for giving the starting apparatus the 125 slow initial movement to facilitate the coupling of the starting apparatus to the engine.

In this way, the operator is sure that in facilitating the starting operation, and as a 130 part thereof, he is at the same time closing

his ignition circuit so that he is thus sure to have a live ignition circuit for the engine starting operation.

Now, assuming that the engine has been started in the manner above referred to, the operator may leave the push button 420 latched in its depressed position, and utilize the vibrating spark ignition system, or he may operate either the button 421 or 459 and thereby utilize a single spark battery ignition or a magneto ignition.

The operation of either one or the other of these buttons 421 and 459 is arranged to release the vibrator button 420, and this is of course a preferable operation because less current is thereby utilized from the battery for the ignition purpose.

Then when it is desired to cease the operation of the engine, the release button 131 is operated, which releases either one of the buttons 421 and 459, in case they have been depressed for the ignition system operation, or to release the vibrator button 420 in case that has been utilized.

The particular construction of the switch mechanism itself for accomplishing the latching-in of the various push buttons of the button releasing devices above referred to, will now be described.

The general form of the push button switch is shown in Fig. 2. This shows the face of the switch with the four previously mentioned buttons 420, 459, 421 and 131, projecting outwardly from the face.

The numeral 100 represents an outer casting having an extended shell portion 102, wherein certain of the operating elements are contained. These elements include a main supporting plate 104, (Fig. 5), on which is mounted a latching detent plate 106. A spring 107, secured to the detent plate at 105 and to a projecting pin 108 (which pin extends through to the plate 104), holds the detent plate normally in one position. This detent plate is adapted to be oscillated against its spring tension, whenever one of the said push buttons is pushed inwardly, and then to return under its spring tension to normal position, but thereby latching the button in its depressed position.

The push buttons are normally held in outward position by springs 125 (see Fig. 3). The inner end of each button comprises a flange 127, separated from the beveled portion 128 by a groove 129. The extreme end portion of the button is reduced as at 130.

The location of the beveled portion 128, with reference to the detent plate 106, is such, (as shown in Fig. 6), that when the button is pressed inwardly, the beveled portion 128 will strike the edge of the detent plate 106, oscillating it against its spring tension enough to let the beveled portion of the button slide by the detent plate, and then

the detent plate snaps into the groove 129, thereby latching the button in its depressed position.

It is the inward pressing of these buttons which closes the contacts as previously described, this actual contact closing operation being described presently.

As previously referred to, each one of the buttons 420, 421, and 459 may be arranged in this manner to be latched in its normal position for closing the respective contacts. But, as already referred to in the original application, of which the present application is a division, the vibrator button 420 may be constructed without the latching provision, in which case, obviously, there would be no such groove 129 for latching by the detent plate.

As is common in key latching mechanism of this sort, it will be obvious that the construction of this flange portion 128 would be such that when any one of the three buttons referred to, had been depressed, the depressing of one of the other or inoperative buttons, would oscillate the detent plate, thus releasing the previously latched-in button and then latching inward the now operated button.

But the releasing button 131 is also provided so that when any one of the three lower buttons is depressed and latched, the depressed button may be released by mere pressing inward of the top button 131. To perform this releasing function, the push button 131, has no latching groove corresponding to the groove 129, but simply has a beveled portion corresponding to the portion 128, so that this beveled portion strikes the detent plate 106 and oscillates it to release any one of the other depressed buttons, but of course the button 131 would not be latched in because it has no latching groove. A spring similar to the spring 125, restores the releasing button 131 to its normal outward position.

The parts shown in Fig. 5 represent the locking mechanism, whereby a key 151 inserted into the lock 150, operates by the turning of the cylindrical element 145, to force the slotted plate 143 to one side, against the tension of the spring 143^a, so as to carry the projection 153 into the path of one of the lobes of the locking detent shown in Fig. 6. This prevents the locking detent from movement and thus prevents any of the keys from being depressed.

The mechanism for closing the various contact elements by the pressing of the push buttons referred to, is shown in Fig. 4.

Referring to Fig. 1, it will be seen that of the various push button contact strips, three of them, namely 38, 178 and 60, are on the under sides; so that viewing these parts of the switch mechanism from the under side, as shown in Fig. 4, these three elements 130

are shown in their respective positions, extending outwardly from the point of attachment to the main body portion 104.

Considering for example the contact strip 38, it will be seen that there is another strip 21 (Fig. 1), which overlies contact strip 38. This strip in Fig. 4 is of course not shown, because it is behind strip 38. But, when the button 421 is depressed, its inner end 10 130 (see Fig. 3), first comes in contact with the strip 21, and then presses it downwardly into engagement with the strip 38 shown in Fig. 4.

The push button itself may be made of insulating material, or it may have a strip of insulating material intervening between the push button and the contact plates, as shown in Figs. 4 and 5, so that the pressing inward of the button, will not short circuit 20 the current, but will be prevented from doing so by the insulation.

There is a similar arrangement of contacts for the other push buttons, and in addition, for the vibrating button 420, Fig. 4, 25 shows the additional contact plate 438 which extends outward from the central portion of the switch, so that it may be connected to a terminal connected to the wire to follow out the circuit arrangement of diagrammatic Fig. 1. The vibrator button 420 strikes directly on the plate 438.

In Fig. 7 is shown the double binding post which may conveniently be used with this type of switch. The metal part of the 35 switch, namely the parts 100 and 102 constitutes the ground portion of the circuit, referred to in diagrammatic Fig. 1. By this means, the push button 420 is included directly in the circuit.

40 The central stud 505 of the binding post shown in Fig. 7, passes through the supporting plate 104^a, and occupies the position at the central portion of the switch shown in Fig. 4. Thus, the central portion 45 505 of the binding post is in mechanical and electrical connection with the supporting plate 104^a and thus grounded. The other extremity of the binding post has a clamping element 472. The wire 441 is connected to the clamping element 472, and thus to the supporting plate 104^a, which constitutes the ground connection to connect this circuit to the push button 420.

Surrounding the center portion 505 is an 55 insulating sleeve 506. This in turn is surrounded by a sleeve 507 which is reduced at 508, to form an abutment for the coil spring 509. Over the sleeve 507 is a sliding sleeve 507^a. This sleeve is adapted to move to the 60 left in Fig. 7, against the tension of the spring 509, so that the contact terminal 439 may be slipped in between the sliding sleeve 507^a and the body portion of the binding post. The effect of this is to connect the 65 wire 439 to the metallic sleeve 507^a.

Then this entire binding post is screwed into the center portion of the switch, so that the under shoulder of the sleeve 507^a comes directly in contact with the contact plate 438, shown in Fig. 4. That is, in Fig. 4, it is to 70 be understood that this double binding post is secured directly into the central portion of the switch itself, so as to bring the sleeve 507^a into contact with the plate 438, as described.

75 The effect of this is to connect the wire 439 to the plate 438, in the manner explained in diagrammatic Fig. 1. At the same time, the wire 441 is shown in Fig. 7 as connected to the other terminal clip 472 80 of the binding post, whereby to ground this wire and thus connect it to the push button 420 and in this manner carry out the diagrammatic showing of Fig. 1.

85 While the above described mechanisms constitute a preferred form of embodiment of our invention, it is to be understood that other forms might be utilized within the scope of the claims which follow:

What is claimed is as follows:

90 1. In a system of electrical distribution, the combination with an electric machine having a slow initial starting circuit and an ignition circuit; of a selective switch comprising an element for closing the starting 95 circuit concurrently with the closing of the ignition circuit.

2. In a system of electrical distribution, the combination with an electric machine having a slow initial starting circuit and a 100 plurality of ignition systems; of a selective switch for controlling the ignition systems and starting circuit, whereby the starting circuit and the ignition systems may be brought into operation concurrently or the 105 ignition systems may be brought into operation independent of the starting circuit.

3. In a system of electrical distribution, the combination with an electric machine, having a slow initial starting circuit, and 110 ignition systems of the magneto type, single spark battery type and vibrating spark type; of a selective switch for controlling said starting circuit and ignition systems, comprising independent elements for controlling the magneto type of ignition and the 115 single spark battery type of ignition; and an independent operating element for concurrently controlling the closing of the starting circuit and the establishing of the 120 vibrating spark circuit.

4. In a system of electrical distribution, the combination with an electric machine, having a slow initial starting circuit, and ignition systems of the magneto type, single 125 spark battery type and vibrating spark type; of a selective switch for controlling said starting circuit and ignition systems, comprising independent elements for controlling the magneto type of ignition and 130

- the single spark battery type of ignition; and an independent operating element for concurrently controlling the closing of the starting circuit and the establishing of the 5 vibrating spark circuit; and means coöperating with said controlling elements, whereby all of said elements may be operated concurrently.
5. In a system of electrical distribution, 10 the combination with an electric machine, having a slow initial starting circuit, and ignition systems of the magneto type, single spark battery type and vibrating spark type; of a selective switch for controlling said 15 starting circuit and ignition systems, comprising independent elements for controlling the magneto type of ignition and the single spark battery type of ignition; and an independent operating element for concurrently 20 controlling the closing of the starting circuit and the establishing of the vibrating spark circuit; and means for maintaining the elements for controlling the single spark battery type of ignition and the magneto 25 type in operative position without interfering with the operation of the element for controlling the starting circuit.
6. In a system of electrical distribution, the combination with a starting and ignition system for combustion or explosion engines; 30 of a selective switch including a push button element operable to effect the initial operation of the starting system to facilitate the connection of the starting system with the engine and to concurrently bring said 35 ignition system into operative condition, whereby ignition will be furnished to the engine, incident to the starting operation thereof.
7. In a system of power distribution and 40 control, the combination with an engine; of a starting and ignition system therefor; and a controlling element for imparting a slow initial movement to said starting system, incident to the establishment of the ignition 45 system.

In testimony whereof we affix our signatures in the presence of two subscribing witnesses.
